CLAIM

The ornamental design for a mobile trolley stand, as shown and described.

DESCRIPTION

FIG. 1 is a perspective view of a mobile trolley stand showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof in a folded configuration.

The broken lines shown in FIG. 7 illustrate portions of the mobile trolley stand that form no part of the claimed design.

1 Claim, 8 Drawing Sheets
